[57] CLAIM

The ornamental design for an aircraft, as shown and described.

DESCRIPTION

FIG. 1 is a top plan view of an aircraft showing my new design;

FIG. 2 is a side elevational view thereof, the opposite side view being a mirror image of that shown;

FIG. 3 is a front elevational view thereof;

FIG. 4 is a bottom plan view thereof;

FIG. 5 is a rear elevational view thereof;

FIG. 6 is a top perspective view thereof;

FIG. 7 is a bottom perspective view thereof; and

FIG. 8 is a bottom plan view of a second embodiment of the aircraft. The top, side, and rear views of the second embodiment are identical to FIGS. 1, 2, 3, 5, and 6.

FIG. 3

FIG. 4

FIG. 5

FIG. 6

FIG. 7
